[57] CLAIM

The ornamental design for a contoured merchandiser, as shown and described.

DESCRIPTION

FIG. 1 is a front elevational view a contoured merchandiser showing my new design;

FIG. 2 is a rear elevational view thereof;

FIG. 3 is a right side elevational view thereof; the left side elevational view is identical but in mirror image;

FIG. 4 is a top plan view thereof; and,

FIG. 5 is a bottom plan view thereof.

The broken line showing is for illustrative purposes only and forms no part of the design.
